US0D1053245S

(12) **United States Design Patent** (10) **Patent No.:** **US D1,053,245 S**
Bedier et al. (45) **Date of Patent:** ** *Dec. 3, 2024

(54) **ELECTRONIC PAYMENT TERMINAL**

(71) Applicant: **Poyn** LLC, Tempe, AZ (US)

(72) Inventors: **Osama Bedier**, Palo Alto, CA (US);
Ray Tanaka, Palo Alto, CA (US);
Robert Hernandez, Palo Alto, CA (US)

(73) Assignee: **Poyn** LLC, Tempe, AZ (US)

(*) Notice: This patent is subject to a terminal disclaimer.

(**) Term: **15 Years**

(21) Appl. No.: **29/873,363**

(22) Filed: **Mar. 30, 2023**

Related U.S. Application Data

(63) Continuation of application No. 17/962,296, filed on Oct. 7, 2022, now Pat. No. 11,829,980, which is a continuation of application No. 17/186,331, filed on Feb. 26, 2021, now Pat. No. 11,468,419, which is a continuation of application No. 16/700,145, filed on Dec. 2, 2019, now Pat. No. 10,977,637, which is a continuation of application No. 16/119,072, filed on Aug. 31, 2018, now Pat. No. 10,528,934, which is a continuation of application No. 15/635,462, filed on Jun. 28, 2017, now Pat. No. 10,096,012, which is a continuation of application No. 14/743,356, filed on Jun. 18, 2015, now Pat. No. 9,721,247, which is a continuation of application No. 14/526,033, filed on Oct. 28, 2014, now Pat. No. 9,092,766.

CLAIM

The ornamental design for an electronic payment terminal as shown and described.

DESCRIPTION

FIG. 1 is a front perspective view of an electronic payment terminal.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The oblique lines represent transparent material.

The dash-dot broken lines illustrate portions of the article that form no part of the claimed design. The dash-dot-dash

broken lines illustrate the bounds of the claimed design and
form no part of the claimed design.

1 Claim, 7 Drawing Sheets
